UNITED STATES PATENT OFFICE.

MAXIMILIAN SCHILLER, OF PHILADELPHIA, PENNSYLVANIA, ASSIGNOR TO
EDWARD OPPENHEIMER, SR., OF PHILADELPHIA, PENNSYLVANIA.

MEANS FOR HOLDING SYMBOLS IN FRAMES.

1,135,726.

Specification of Letters Patent. Patented Apr. 13, 1915.

Application filed August 8, 1914. Serial No. 855,716.

To all whom it may concern:

Be it known that I, MAXIMILIAN SCHILLER, a subject of the Emperor of Germany, residing at Philadelphia, in the county of Philadelphia and State of Pennsylvania, have invented certain new and useful Improvements in Means for Holding Symbols in Frames, of which the following is a specification.

My invention relates to means to hold symbols in the frames of belt buckles, pins and other devices of similar character in which letters or monograms or other symbols are employed for ornamentation, identification and other purposes.

The object of my invention is to provide a novel, simple and efficient device of the character above mentioned in which different letters or symbols may be readily applied to or removed from the frame of the device, and to this end my invented device consists of the elements and the combinations of them hereinafter fully described and claimed.

In the accompanying drawings, illustrating my invention, Figure 1, is a front view of my improved device. Fig. 2, is a side view thereof. Fig. 3, is a back view of the device. Fig. 4, is a section, on line 4—4 of Fig. 3. Fig. 5, is a back view of the device, showing the symbol retaining arms in the open or inoperative position. Fig. 6, is a detail showing the slotted lug to receive one of the symbol retaining arms. Fig. 7, is a detail showing the slotted lug bent to hold the symbol retaining arm in the operative position. Fig. 8, is a detail showing a modification of the invention.

Referring to the drawings, 2 designates a flat frame comprising top and bottom bars 3 and end bars 5, formed integral with each other and surrounding a central opening 6 across which the letters or symbols 7 are located. This frame 2, as herein shown, is designed to be used as the main body of a belt buckle, but, obviously, the frame may constitute the main body of an ornamental pin or any other device in which it is desired to use letters or symbols, either for ornamentation or identification or both.

The back of the top and bottom bars 3 of the frame 2 have depressions 8 therein in which retaining pins 9 are located. The top and bottom of the letters or symbols 7 have projections 10 thereon which extend into the depressions 8 and surround the pins 9, the

pins 9 being suitably spaced to hold the letters 7 in proper lateral relation.

Pivoted, at 11, to the back of the frame 2 are flat arms 12 which are movable to an operative position, as shown in Fig. 3, and to an inoperative position shown in Fig. 5. When the arms 12 are in the operative position, they lie flat against the back of the top and bottom bars 3 and against the back of the projections 10 and thus hold the letters 7 firmly in place between the walls of the depressions 8 and the arms 12, the space between such walls and the arms being substantially equal to the thickness of the projections 10 on the letters 7. When the arms 12 are moved to or beyond the position shown in Fig. 5, the letters or symbols 7 may be readily removed from or inserted into the frame 2.

The free end of each arm 12 is reduced in width and is adapted to enter a slot 13 in a lug 14 on the frame 2 when the arm 12 is moved to the operative position shown in Fig. 3; and the lug 14 has a free end or part 15, which is adapted to be bent from the condition shown in Fig. 6 to the condition shown in Fig. 7, or into the path of movement of the arm 12 and thus prevent it from moving from the operative position. This part 15 may be bent back to the condition shown in Fig. 6 when it is desired to again move the arm 12 to the inoperative position.

As herein shown, the frame 2 is provided with a loop 16 as a means to attach it to a part of a belt, and the frame 2 is also provided with a pin 17 for coöperation with another part of a belt buckle.

Instead of employing the pins 17 and a single depression 18 in each bar 3, I may arrange projections 18 of the letters 7 in suitable spaced, separate depressions 19 in the bars 3, as shown in Fig. 8. In such case, the opening in the projections would be dispensed with and the letters would be held properly spaced from each other by the walls 20 between the depressions 19.

I claim:

1. In a device of the character described, a frame having a depression in the back thereof; a symbol having a part extending into said depression; an arm pivoted to the back of said frame and movable on its pivot into an operative position, retaining said part in said depression, and movable into an inoperative position, permitting the removal

of said part from said depression, and a lug on said frame having a slot therein into which said arm moves when moved to its operative position, said lug having a part arranged to be bent into the path of movement of said arm and prevent its movement from the operative position.

2. In a device of the character described, a frame having a depression in the back 10 thereof; a symbol having a part extending into said depression; a flat arm having a broad forward face adjacent the back face of said frame and pivoted to said frame on a pin extending substantially at right angles 15 to said faces; said arm being movable edge-wise on its pivot into an operative position,

retaining said part in said depression, and movable into an inoperative position, permitting the removal of said part from said depression, and a lug on said frame having a slot therein into which said arm moves when moved to its operative position, said lug having a part arranged to be bent into the path of movement of said arm and prevent its movement from the operative position. 20 25

In testimony whereof I affix my signature in presence of two witnesses.

MAXIMILIAN SCHILLER.
